VALVE SPRING LIFTER LOCK

Filed March 9, 1921

Inventor:
Harry W. Kulp & Martin C. Dellinger

By Wm H. Balow & Son

Atty's.

UNITED STATES PATENT OFFICE.

HARRY W. KULP AND MARTIN C. DELLINGER, OF LANCASTER, PENNSYLVANIA.

VALVE-SPRING-LIFTER LOCK.

Application filed March 9, 1921. Serial No. 450,902.

To all whom it may concern:

Be it known that HARRY W. KULP and MARTIN C. DELLINGER, citizens of the United States, residing at Lancaster, in the county 5 of Lancaster and State of Pennsylvania, have invented certain new and useful Improvements in Valve-Spring-Lifter Locks, of which the following is a specification.

The present invention relates to valve 10 spring lifters, and more particularly to a locking device for automatically holding or securing the lifter in any one of a wide range of varying positions.

The main purpose of the invention is to 15 counteract the force of the compressed spring in the operation of the tool. The tendency of the compressed spring is to close the jaws, thereby spreading the handles. This, of course, necessitates a continuous 20 squeezing action on the handles by the operator. But, to be of any real use, the lock must be entirely automatic and instantly operative, so that the handles will be arrested the instant that the spring starts their closing 25 movements. Also, it must be so constructed and arranged that it may be instantly released so that the tool may be removed. And, as a practical commercial device, it should not project through or beyond 30 either handle, but should lie entirely between them, at all times. The present invention is designed especially to accomplish these and other purposes and to provide a simple, compact, inexpensive, sensitive, automatic lock of the character described. 35

In the drawings:

Fig. 1 is a side elevation of the invention, with the handles open, and the top or upper handle broken away, to more clearly show 40 the operation of the locking plate;

Fig. 2 is a vertical cross-section through the upper handle member in the rear of the locking plate, showing the locking plate in elevation, looking in the direction of the 45 jaw;

Fig. 3 is an enlarged fragmentary view showing the locking plate released, and

Fig. 4 is a similar view, showing the plate in holding position, binding against the opposite sides or edges of the bar.

The lifter, as a whole, is constructed and operates as in the prior Patent 1,330,542, H. W. Kulp, granted Feb. 10, 1920 to which reference is hereby made. To the inner face

of one of the handles 1 is movably secured 55 an arcuate bar 2 having a lower ratchet edge 3. A pivot pin 4, passed through the end of the bar and the upturned side walls of the handle, permits free swinging movement of the bar relatively to the handle. 60 Through a lateral slot 5 in the other handle, slightly to the rear of the pivot pin 4, is extended a locking plate 6 having shoulders 7 adapted to engage the outer face of the handle to prevent the plate from passing inwardly completely through the handle, while at the same time providing a rocking edge or fulcrum on which the plate may be 65 rocked, for a purpose to be later disclosed. The part projecting through the handle is 70 provided with an opening 8 of substantially the same size and shape as a lateral cross-section of the bar 2 and adapted to slidably receive the bar. On reference to Fig. 1, more especially, it will be seen that the plate 75 6 extends at a slight angle to the radius of the bar 2. The result is a binding action between the ratchet edge 3 and contacting inner wall of opening 8, on the one hand, and a similar engagement between the inner 80 wall at the opposite end of opening 8 and the other edge of the bar 2. This engagement is maintained by the spring 9 connected at its opposite ends, respectively, with the plate 6 and with a pin or stud 10 in 85 the handle 1. Due to the relative positions of the parts, any tendency to spread or open the handle will, obviously, increase the binding or locking action between plate 6 and bar 2. On the other hand, any closing 90 action of the handles will act reversely, the engaged tooth of bar 2 carrying the inner end of plate 6 rearwardly until it reaches a position substantially radial to the arc of bar 2. It will then escape from that tooth 95 and its spring will draw it into engagement with the next tooth, making an audible click as it engages. The bar, swinging downwardly on its pivot, as the handles approach each other, will slide freely through the opening 100 in the plate. Any effort to spread the handles will meet with the same result as before. Thus, the handles are automatically locked against spreading, at practically any desired point, the ratchet teeth being comparatively 105 small and closely spaced. In order to effect quick release of the plate, it is only necessary to press forward the head 11 of plate

6 so that it will assume a position substantially radial to the arc of bar 2. The bar will then slide freely through plate 6, in either direction. The head is so placed and 5 constructed as to be readily engaged by the thumb of the operator when using the tool. Preferably, the free end of the bar is tapered or bevelled, as at 12, so that it may be readily and quickly inserted through the 10 opening 8.

It is thought that the construction, operation, and use of the invention will be clear from the preceding detailed description.

It is clear that the invention may be 15 equally well applied to many other tools and implements than the one shown, the one shown serving simply as an illustration of one general use.

Obviously, changes may be made in the 20 construction, arrangement and disposition of the several parts of the invention, within the scope of the claims, and it is meant to include all such within this application wherein only one preferred form has been 25 disclosed, by way of illustration.

Having thus described our invention, what we claim and desire to protect by Letters Patent is:

1. In combination in a valve spring lifter, 30 a pair of movably mounted handles, a bar movably mounted in one of said handles and at all times lying entirely between said handles, and a locking plate extending through the other handle and operatively engaging said bar.

2. In combination in a valve spring lifter, 40 a pair of movably mounted handles, a bar movably mounted in one of said handles and at all times lying entirely between said handles, a locking plate extending through the other handle and operatively engaging said bar, and means for disengaging said locking plate.

3. In combination in a valve spring lifter, 45 a pair of movably mounted handles, a bar movably mounted in one of said handles and at all times lying entirely between said handles, a locking plate extending through the other handle and operatively engaging said bar, and means for maintaining said locking plate normally in engagement.

4. In combination in a valve spring lifter, 55 a pair of movably mounted handles, a bar movably mounted in one of said handles and at all times lying entirely between said handles, a locking plate extending through the other handle and operatively engaging said bar, means for maintaining said locking plate normally in engagement, and means 60 for disengaging said plate.

5. In combination in a valve spring lifter, 65 a pair of movably mounted handles, a jaw carried by each handle, an arcuate bar movably mounted in one of said handles and lying entirely between said handles at all times, and

locking means engaging said bar, and preventing movement of said handles to close the jaws thereof.

6. In combination in a valve spring lifter, 70 a pair of movably mounted handles, an arcuate bar movably mounted in one of said handles and provided with ratchet teeth on its concave edge, and a locking plate rockably mounted in the other handle and provided with an opening adapted to slidably receive 75 said bar in such manner that its opposite walls will engage said ratchet teeth and the convex edge of the aforesaid bar, respectively, said plate being provided with a head projecting beyond the handle and adapted 80 to be engaged to release the locking plate.

7. In combination in a valve spring lifter, 85 a pair of movably mounted handles, a jaw carried by each handle, an arcuate bar movably mounted in one of said handles, and a locking plate movably mounted in the other handle and provided with an opening to slidably receive said bar, said plate engaging said bar and automatically locking the same to prevent movement of said handles 90 to close the jaws carried thereby.

8. In combination in a valve spring lifter, 95 a pair of movably mounted handles, an arcuate bar movably mounted in one of said handles and having one ratchet edge and an opposite smooth edge, and a locking plate movably mounted in the other handle and provided with an opening to slidably receive said bar, said plate being adapted to simultaneously engage the opposite edge of said 100 bar to bind the same and lock the lifter in adjusted position.

9. In combination in a valve spring lifter, 105 a pair of movably mounted handles, an arcuate bar movably mounted in one of said handles and having one ratchet edge and an opposite smooth edge, a locking plate movably mounted in the other handle and provided with an opening to slidably receive said bar, said plate being adapted to simultaneously engage the opposite edges of said bar to bind the same and lock the lifter in adjusted position, and means for maintaining 110 said plate in engagement with said bar.

10. In combination in a valve spring lifter, 115 a pair of movably mounted handles, an arcuate bar movably mounted in one of said handles and having one ratchet edge and an opposite smooth edge, a locking plate movably mounted in the other handle and provided with an opening to slidably receive said bar, said plate being adapted to simultaneously engage opposite edges of said bar to bind the same and lock the lifter in adjusted position, means for maintaining said 120 plate in engagement with said bar, and a thumb piece extending from said plate by which said plate may be actuated to releasing position.

11. In combination in a valve spring lifter, 125

a pair of movably mounted handles, a bar movably mounted in one of said handles, a locking plate extending through the other handle, rockably mounted therein and operatively engaging the opposite edges of said bar and binding the same in locked position; means for normally maintaining locking engagement of said plate with said bar, and a thumb piece extending from said plate and adapted to be engaged to actuate said plate to releasing position.

12. In combination in a valve spring lifter, a pair of movably mounted handles, a bar movably mounted in one of said handles and at all times lying entirely between said handles, a locking plate extending through the other handle and operatively engaging said bar and being adapted to be automatically disengaged by closing of the aforesaid handles, and means normally maintaining said locking plate in operative locking engagement with said bar.

13. In combination in a valve spring lifter, a pair of movably mounted handles, a bar movably mounted in one of said handles and at all times lying entirely between said handles, a locking plate extending through the other handle and operatively engaging said bar and being adapted to be automatically disengaged by closing of the aforesaid handles, and means normally maintaining said locking plate in operative locking engagement with said bar, said plate being provided with a thumb piece whereby it may be rocked to release said bar.

In testimony whereof we have signed our names to this specification in the presence of two subscribing witnesses.
